UNITED STATES PATENT OFFICE.

FELIX EMILE VALOIS, OF HAVERHILL, MASSACHUSETTS, ASSIGNOR TO HAMEL SHOE MACHINERY COMPANY, OF LYNN, MASSACHUSETTS, A CORPORATION OF MASSACHUSETTS.

STOP MOTION FOR SHOE-SEWING MACHINES.

1,422,639.

Specification of Letters Patent.

Patented July 11, 1922.

Application filed July 31, 1916. Serial No. 112,230.

To all whom it may concern:

Be it known that I, FELIX EMILE VALOIS, a citizen of the United States, residing at Haverhill, county of Essex, State of Massachusetts, have invented a certain new and useful Improvement in Stop Motions for Shoe-Sewing Machines, of which the following is a specification, reference being had therein to the accompanying drawings.

10 My invention relates to a stop motion for use on sewing machines of various kinds, and particularly shoe sewing machines such as welt, turn or outsole stitchers, to relieve the operator of the work of stopping the 15 machine by hand at the proper position in its cycle of motions.

Shoe sewing machines as heretofore constructed have ordinarily been provided with a hand wheel by which the operator stops 20 the machine and by which he turns the machine backward or forward to separate the stitch forming instrumentalities and permit the work to be inserted or removed; also to permit the thread to be drawn out before 25 beginning to stitch another shoe. This makes it necessary for the operator to use one hand to stop and turn back the machine and consequently delays him in his work.

My present invention provides an automatic mechanism by means of which the machine will be stopped when the foot treadle by which the operator controls the machine is released. The machine will be stopped quickly even when running at low speed and will come to rest with the stitch forming instrumentalities in separated position ready for the insertion or removal of the work. The machine also operates automatically to release the tension on the 40 thread so that the thread may be drawn out more easily. It is also arranged so that the stitch forming instrumentalities will skip a stitch just as the machine stops.

The general mode of operation of the 45 machine embodying my invention differs fundamentally from devices of a similar character which have heretofore been employed. Heretofore, the stop motion has acted first to slow down the machine from the high speed at which the machine runs 50 during the stitching operation to a low speed, thereafter bringing the machine to rest at a predetermined point while the machine

is being driven at low speed. The result has been that an unnecessarily large proportion of the time has been consumed in stopping and turning back the machine to separate the stitching instrumentalities. This has sometimes been accomplished by having high speed driving mechanism and 55 a low speed driving mechanism, and the stop motion acts to change the drive from high speed to low speed, and then to stop the machine.

In a machine embodying my invention, 60 the stop motion first operates to connect the machine so that it will be operated at full speed during the formation of the last stitch, then disconnects the driving mechanism and stops the machine. If for instance 65 the operator wants to stop the machine after sewing some portion of the work which requires to be sewn slowly, the stop motion first puts the machine into high speed for a single stitch and then stops it in the pre- 70 determined position in the cycle of operation. The result is that the output of the machine is very much increased. I find that the mechanism embodying my invention will stop the machine with no noise 75 or jar even though it is being driven by the high speed drive at full speed.

The machine is so constructed that a single belt is employed even though the machine can be run at a range of speeds. The stop 80 motion may be disconnected by moving a single lever, and thereafter the machine can be operated by the hand wheel as in the past.

It is possible also to stop the machine by letting up the treadle enough to disconnect the driving clutch but not enough to set the stop motion in action, the machine under these conditions stopping by loss of momentum with the stitching instrumentalities still in the work. This is convenient for 90 many reasons as it gives the operator a chance to examine the work whenever he desires. It also permits the use of the machine on a greater range of work, as for instance on welt shoes where the welt is 100 sewed all the way around the upper. In this case the operator will let up the treadle just enough to disconnect the drive allowing the machine to stop; he will then cut off the welt, depress the treadle and continue 105 the stitching until he reaches the starting

point, when he will release the treadle and the stop motion will stop the machine. The machine is also capable of other special uses which need not be described.

5 In the following description, I have described mechanism, by means of which the stitching instrumentalities namely, the needle and looper are separated when the machine is stopped to facilitate the insertion or removal of the work. This is accomplished by mechanism acting upon the needle. I do not limit myself, however, to this construction since it will be obvious to those skilled in the art that it is only 10 necessary that the needle and looper be separated sufficiently. I have also shown my device as applied to a shoe sewing machine because that is the way in which I have put the device into actual use, but I do not limit myself to this application of it 15 since it is capable of use in combination with other machines.

The invention will be fully understood when taken in connection with the accompanying drawings and the novel features thereof will be pointed out and clearly defined in the claims at the close of this specification.

In the drawings, Fig. 1 is a front elevation of mechanism embodying my invention, certain parts being in section and only so much of the sewing machine being shown as is necessary for an understanding of the present invention.

35 Fig. 2 is a top plan view partly in section of the devices shown in Fig. 1.

Fig. 3 is a section on line 3—3 of Fig. 1 looking in the direction of the arrows.

Fig. 4 is a side elevation of the cam 37.

40 Fig. 5 is an end view of the cam shown in Fig. 4.

Fig. 6 is a detail of the stop cam and the upper end of the stop lever, the parts being in the position occupied while the machine 45 is being stopped.

Referring now to the drawings, there is shown, at A, the frame of the machine, at B the main driving shaft, at C the driving pulley and at D a hand wheel, said hand 50 wheel being fast to the main shaft B. Interposed between the driving wheel C and the hand wheel D is a leather disk 11 fastened to the face of the hand wheel or of the driving wheel. It will, therefore, be 55 understood that when the driving wheel C is moved to the left, the hand wheel D and main shaft B will be caused to rotate by frictional contact. At E is shown the needle (see Fig. 3) and at F the looper. The needle 60 is mounted on the oscillating needle sector G which is operated by the cam H through the bell crank lever L and curved link K. At P is shown the treadle by means of which the machine is controlled by the operator. The treadle P is connected by a

chain or wire M to the lower end of a treadle bar 13 movable vertically in a guideway formed by a groove in the frame of the machine and a cover 14 secured thereto. The treadle bar 13 is provided on its rear 70 face as seen in Fig. 1 with a short rack 15 which meshes with a pinion 16 on a shaft 17. The shaft 17 carries an eccentric 18, see Fig. 3, which forms the pivot for the bell crank L by means of which the needle sector G is oscillated. When the treadle P is depressed, the eccentric 18 is rotated so that the axis of oscillation of the bell crank L is in proper position for the running of the machine. When the treadle bar is in its 75 upper position, this being just before the automatic stop motion stops the machine, the eccentric 18 changes the position of the axis of oscillation of the bell crank L so that the needle E is drawn away from the looper F 80 just enough so that the looper will lay the thread across the point of the needle instead of laying it under the barb of the needle. This makes the machine skip the last stitch. The eccentric is so positioned on the shaft 90 17 that the axis of oscillation will not be moved appreciably by the first part of the upward movement of the treadle bar, the effective movement taking place just before it reaches the top of its stroke. By this 95 means the treadle bar may be moved sufficiently to control the speed of the machine without causing it to skip a stitch except when the treadle bar is allowed to move its full stroke.

The upper end of the treadle bar 13 is provided with a roll 19 which rests on a hard wearing surface 20 formed on the end of an arm 21 of a rock shaft 22. This rock shaft has two arms 23 and 24 carrying rolls 25 100 which form a clutch shifter and which are located in a groove 26 of the clutch hub 27 of the driving wheel C. When the treadle P is depressed, this mechanism pushes the hub 27 to the left as seen in Fig. 1, and produces a frictional engagement sufficient to drive the hand wheel D and thus the machine. For convenience, these parts may be referred to as the "variable speed clutch." The pressure exerted on the treadle P by the 110 operator will regulate the speed of the machine. The greater the pressure, the faster the machine will run until it is revolving at the same speed as the main driving wheel C. The treadle bar 13 is held up by a spring 93 115 which is strong enough to lift the bar and attached parts. As will be explained more fully later, the treadle bar actuates the stop motion, but the treadle bar has a range of motion sufficient to vary the speed of the machine from full speed down to a point where the clutch is disengaged and the machine can stop by loss of momentum, the purpose being to make it possible for the workman to run the machine at any speed 120 125 130

or even to stop it by hand in the old way without the interposition of the stop motion.

The treadle bar 13 is provided on its side edge with a notch 28 within which is received the end of a finger 29 formed on a lever 30 pivoted at 31 to the frame of the machine. The finger 29 is guided in a slot formed in the cover 14 in which the treadle bar slides. The lever 30 carries a small 10 roller 32 moving in a cam slot 33 formed in a cam 34 located on the main shaft B. A spring 94 holds the roller 32 in contact with the cam 34. This cam roll operates to move the lever 30 and withdraw the finger 29 from the notch in the treadle bar so that the treadle bar can be moved above a predetermined point only when the main shaft is in a certain position. This prevents the machine being automatically stopped until 15 the next revolution in case the thread has already been laid in the barb of the needle at the time when the operator releases the treadle. The upper edge of the notch 28 in the treadle bar is rounded or inclined so that 20 the treadle bar can be pulled down by the treadle even when the finger 29 is in the slot but whenever the finger is in the notch it will prevent the treadle bar being raised 25 above the predetermined point.

30 On the main shaft B is located the cam H by which some of the stitching instrumentalities are operated. The periphery of this cam serves as a brake wheel and is engaged by a brake 36 which is operated by the stop 35 motion in a manner which will be described hereafter. There is also located on the main shaft B, a stop cam 37 having a hub 38 (see Fig. 3) which acts as one member of a roll clutch of the well known Horton type represented, for example, in U. S. Patent No. 260, 40 394, of July 4, 1882, the outer member being designated 27 and the intermediate member or roll carrier being designated 39. For convenience this clutch may be referred to 45 as the full speed clutch. When the clutch hub 27 on which the drive wheel C is mounted is moved to the right as shown in Fig. 1, it engages the face 39^x of the roll carrier 39 of the full speed clutch and advances the roll 90 relative to the hub 38, carrying them into wedging engagement between the inclined surfaces 91 of the hub 38 and the internal cylindrical driving surface 27' of the outer clutch hub 27, thus 50 locking the hub 27 roll carrier 39 and hub 38 together and thereafter causing the main shaft to be driven at the same rate of speed as the drive wheel C, until the roll carrier 39 and the hubs 27 and 38 are knocked apart. 55 The roll carrier is provided on its exterior with a tooth 48 which assists in effecting the knocking apart of the roll carrier and the hubs.

60 The stopping of the machine is effected by the following mechanism: At 40 is shown

a swinging stop lever pivoted on trunnions 41, 42 to the frame of the machine. A spring 43 exerts a pressure on the upper end of the stop lever 40 and pushes it toward the cam 37 previously referred to. The 70 stop lever 40 is hollow and contains a spring 44 which surrounds a pin 49 which also serves as a cam follower and carries a collar 45 against which the upper end of the spring 44 rests. The collar 45 is provided with an 75 arm 54 which extends sideways through a slot 55 in the side of the stop lever 40. The upper end of the spring pin or cam follower 49 protrudes through the upper end of the stop lever. The stop lever 40 also has an 80 arm or projection 46 protected by a hardened steel face 47. This arm or projection 46 is located so that it may be swung into the path of the tooth 48 on the roll carrier 39 of the full speed clutch. The stop lever 40 85 also has a tail 50 extending across the treadle bar 13 at a point underneath a small roller 51 so that when the treadle bar is depressed the upper end of the stop lever will be swung to the right as shown in Fig. 1 90 and the spring 43 will be compressed to set the parts. The stop lever is held normally in this position by means of a latch 52 pivoted at 53 to the frame of the machine. A spring 92 surrounds the pivot 53 and holds 95 the lower end of the latch 52 to the left as seen in Fig. 1.

The lower end of the latch 52 is normally in the path of movement of the tail 50 of the stop lever and, therefore, holds the 100 spring 43 compressed and the upper end of the stop lever to the right as shown in Fig. 1 until the latch is moved to release the parts.

When the treadle is released and the treadle bar 13 is pulled up by the spring 93, the 105 roller 51 strikes a cam surface b on the latch 52 and pushes it aside so that the spring 43 is then free to act and push the stop lever 40 toward the cam 37. The upper end of the spring pin or cam follower 49 is out of 110 the path of the cam 37 when the parts are in the position shown in Fig. 1. When the stop lever is released and is pushed over by the spring 43, the upper end of the spring pin or cam follower 49 comes into the path of 115 the cam. The shape of this cam will be clearly seen from Figs. 4 and 5. There is an inclined surface c on the end face which runs into a cut away portion d on the edge of the cam and this is followed by a high 120 spot e also on the edge of the cam. A short distance beyond this high spot is a deep notch f. The result of this construction is that when the stop lever 40 is pushed over by the spring 43 the side of the pin 49 rests 125 against the side of the cam 37 so that when it revolves it follows down the incline c moving still further to the left until the end of the pin rests on the edge surface d of the cam. The further movement of the 130

cam pushes down the spring pin 49 and compresses the spring 44, the full limit of movement of the pin being reached when it is on the high spot *e*. Sufficient energy is thus stored in the spring by the cam to actuate the brake, when the spring is released. The further movement of the cam allows the end of the pin to snap up into the notch *f* being operated by the spring 44.

10 This has the effect of applying the brake 36 to the periphery of the cam *H* which serves as a brake wheel, as will now be described.

15 The upper end of the slide rod 55 which carries the brake 36 is provided with a notch in which operates a tooth 56 formed on a rock shaft 57 (see Fig. 1.) This rock shaft 57 has an arm 58 to which is connected the upper end of a link 59. The link 59 is connected at its lower end to a bell crank 60

20 pivoted at 62 to the cover 14 which is secured to the frame of the machine. The bell crank 60 operates a tension release as will be described hereafter. The link 59 has near its lower end a pawl 63 pivoted to it at

25 64. At 65 is shown a stop against which the pawl is normally held by means of a spring 66. The lower end of the pawl 63 is in the path of the arm 54 when the stop lever is being swung over by the spring 43. When

30 the pin 49 has been fully depressed by the action of the cam 37, being at that time on the high spot *e* of the cam, the arm 54 will be under the pawl 63. As soon as the end of the

35 pin 49 rides over the high spot *e* into the notch *f*, the heavy spring 44 will push up the pawl 63 and the link 59 on which it is mounted and will actuate the brake 36 through the rock shaft 57. While I have

40 shown and described herein a brake operated by the spring pin, this is not essential since by properly designing the parts the spring pin itself may be caused to act as a brake by its pressure on the inclined face *d* and high spot *e* of the cam.

45 The upward movement of the spring pin 49 and link 59 also performs other functions. The lever 58 is extended beyond its pivot 57 and is provided with an arm 95 which carries an adjusting screw 96 which is located

50 over an arm 97 formed on one of the arms 24 of the rock shaft 22. The adjusting screw is set so that when the link 59 is moved up by the pin 49 in the stop lever 40, it will contact with the arm 97 and move the rock

55 shaft 22 to slide the hub 27 to the left out of contact with the face of the roll carrier 39, but not enough to cause it to contact with the hand wheel. This prevents the hub 27 rubbing against the roll carrier and causing undue friction.

60 The thread passes around the tension wheel 70 loosely mounted on a stationary shaft 71, the tension wheel being rotated by the thread. On this shaft is mounted a sliding hub 72 which is prevented from rotation

by a spline 73 or in other suitable manner. The hub 72 is normally pressed against the end of the hub of the tension wheel by a spring 74 surrounding the shaft 71 and resting against a thumb nut 98. At 75, 75 are 70 shown felt surfaces forming suitable frictional contacts for the hub of the tension wheel 70. At 76 is shown one arm of a bell crank lever pivoted at 77 to the frame of the machine, the other arm 78 being forked 75 to engage an annular groove in the hub 72. The arm 76 is bent to extend around certain parts of the machine and is connected by a connection 79 to an eye-bolt 80 which passes through the lower end of the bell crank 60. 80 An adjusting nut 81 on the end of the eye-bolt 80 serves to vary the length of the connection. To enable the operator to use the machine without the stop motion, there is provided a small lever 4 which I term the 85 stop-motion cut out which engages a notch 5 in the treadle bar 13. This notch is long enough to allow the treadle bar to be moved enough to operate the variable speed clutch *C* but when the stop motion cut out is in the 90 notch the spring 93 cannot lift the treadle bar high enough to operate the stop motion.

95 The operation of the machine embodying my invention is as follows: It will be assumed that the machine is running on a shoe, the treadle *P* being depressed so that the driving wheel *C* is in frictional contact with the hand wheel *D*. It may also be assumed that the pressure on the treadle is light so that there is considerable slip between the drive wheel *C* and the hand wheel *D* and the machine, therefore is running 100 very slowly and has practically no momentum. If the operator desires to stop the machine, he releases the treadle.

105 When the treadle is released, the spring 93 moves up the treadle bar until the tail of the bell crank 21 contacts with the hooked end of the tail of the latch 52. As the treadle bar moves up, the finger 29 then 110 snaps into the slot 28 in the treadle bar 13 if the movement of the treadle occurs after the thread has been laid in the barb of the needle, and the parts are held by the finger 29 from further movement until the high 115 spot *h* on the cam 34 moves the lever 30 to the right as shown in Fig. 2 and pulls the finger 29 out of the notch 28 in the treadle bar. While the parts are in this position, the operator may depress the treadle again 120 to speed up the machine and can control the speed by the position of the treadle. The finger 29 does not interfere with this movement because the upper corner of the notch 28 in the treadle bar is rounded off. When

125 the finger 29 has been moved by the cam 34 out of the notch 28 in the treadle bar, the spring 93 can raise the treadle bar and the roll 51 being then in contact with the cam surface *b* on the latch 52, the latch is un- 130

hooked from the tail of the bell crank 21 and the spring 85 is thereafter free to move the bell crank. The movement of the bell crank moves the main drive wheel C out of 5 contact with the hand wheel D and then brings the hub 27 in contact with the roll carrier 39 holding these two parts together so forcibly that the roll carrier 39 is momentarily driven at the maximum speed by the 10 drive wheel C. As soon as the roll carrier 39 revolves far enough, the two rollers 90 are wedged between the inclined surfaces 91 and the cylindrical driving surface 27' and lock the two clutch members 27 and 37 together, whereby the main shaft of the 15 machine is also momentarily driven at the maximum speed.

When the treadle bar 13 is lifted up by the spring 93 and the latch 52 is unlocked 20 from the tail of the bell crank 21, it also releases the stop lever 40 so that the spring 43 pushes the stop lever over to the left as soon as is permitted by the change in position of the inclined surface c on the cam 37. The arm 46 on the stop lever 40 gets 25 in the path of the tooth 48 on the roll carrier 39 and stops the movement of the roll carrier disengaging the rolls from wedging relation with the hubs so that from then on 30 the machine is not driven but revolves under its own momentum for about a quarter of a turn, i. e., until stopped in the proper position by the action of the brake. When the upper end of the pin 49 has ridden onto 35 the high spot e of the cam 37, the arm 54 is under the pawl 63. The machine then rotates until the end of the pin 49 snaps into the notch f of the cam 37. This movement sets the brake 36 almost instantly. It also 40 moves the hub 27 out of contact with the roll carrier, and operates the tension release.

When the operator presses down the treadle to start the machine, the following 45 series of movements takes place. The roll 51 on the treadle bar 13 moves the tail 50 of the stop lever 40 down and swings the pin 49 out of the path of the cam 37. This lets the pawl 63 off the arm 54 on the collar 45. The spring 99 is then free to release the 50 brake and re-set the tension release. The downward movement of the roll 51 on the treadle bar 13 allows the latch 52 to swing into the position shown in Fig. 1 with its 55 lower end against the tail 50 on the stop lever. The roll 19 then engages the wearing surface 20 on the bell crank 21 and at the same time, the upper end of the latch 52 hooks onto the said wearing surface 20. The 60 further movement of the treadle downward, pushes the drive wheel C into frictional contact with the hand wheel D, setting the main shaft in motion at a speed determined by the pressure exerted on the treadle. 65 Reference is here made to my copending

divisional application Serial No. 199,402, filed October 31, 1917, wherein the novel features of the stop-motion device which I have disclosed in the present specification are claimed.

70

What I claim is:

1. In combination with a machine including stitching mechanism, driving mechanism therefor, a stop motion which acts on the driving mechanism to increase the speed 75 of the machine and then to stop it, and mechanism acting on the stop motion to prevent it stopping the machine except during a predetermined part of the cycle of operation of the stitching mechanism.

80

2. In combination with a sewing machine having stitch forming instrumentalities and a main shaft, driving mechanism therefor, a cam revolving with the main shaft and stop mechanism which acts on the driving mechanism to increase the speed of the machine and then to stop it, said cam operating to prevent the stop motion stopping the machine except during a predetermined part 85 of the cycle of operation of the stitch forming instrumentalities.

90

3. In combination with a sewing machine having stitch forming instrumentalities, a needle and a needle actuating mechanism, driving mechanism for the machine, a stop motion and mechanism acting on the needle actuating mechanism during the forward movement of the machine to cause it to skip a stitch just before the stop motion stops the machine.

95

4. In combination with a sewing machine having stitch forming instrumentalities including a needle, needle actuating mechanism, driving mechanism for the machine, a stop motion and mechanism acting on the needle actuating mechanism during the forward movement of the machine, and actuated by the stop motion to cause the machine to skip a stitch just before it stops the machine.

100

5. In combination with a sewing machine having stitch forming instrumentalities, driving mechanism for the machine, a stop motion which acts on the driving mechanism to increase the speed of the machine and then 115 to stop it, and mechanism set in motion by the stop motion and acting on the stitch forming instrumentalities to cause them to skip a stitch before the stop motion stops the machine.

110

6. In combination with a sewing machine having stitch forming instrumentalities, driving mechanism for the machine, a stop motion which acts on the driving mechanism to increase the speed of the machine and then 125 to stop it, mechanism acting on the stop motion to prevent it stopping the machine except during a predetermined part of its cycle of operation and mechanism set in motion by the stop motion and acting on 130

the stitch forming instrumentalities to cause them to skip a stitch before the stop motion stops the machine.

7. In combination with a sewing machine having stitch forming instrumentalities including a movable barbed needle and looper, driving mechanism for the machine, a stop motion which acts on the driving mechanism to increase the speed of the machine and then to stop it, means acting on one of the said stitch forming instrumentalities to change its path of movement relative to that of the other so that the thread will not be laid in the barb of the needle and a stitch will be skipped, said means being set in motion by the stop motion just before it stops the machine.

8. In combination with a sewing machine having stitch forming instrumentalities including an oscillating barbed needle, driving mechanism for the machine, a stop motion which acts on the driving mechanism to increase the speed of the machine and then to stop it, means acting on the needle to change the position of its axis of oscillation so that a stitch will be skipped, said means being set in motion by the stop motion just before it stops the machine.

9. In combination with a sewing machine, driving mechanism therefor, stitching instrumentalities and means for causing them to skip a stitch, a stop motion, a treadle bar, connections from the treadle bar to each of the hereinbefore mentioned elements whereby the movement of the treadle bar actuates the said elements, a cam rotating with the driving mechanism and means actuated by the cam to release the treadle bar at a predetermined point in the cycle of the machine.

10. In combination with a sewing machine, driving mechanism therefor, stitching instrumentalities, including a needle, needle actuating mechanism, means for acting on the needle, actuating mechanism during the forward movement of the machine for causing the stitching instrumentalities to skip a stitch, a treadle bar and connections to the hereinbefore mentioned elements whereby the movement of the treadle bar actuates all of said elements.

11. In combination with a sewing machine, variable speed driving mechanism and independent full speed driving mechanism therefor, stitching instrumentalities and means for causing them to skip a stitch, a tension release, a stop motion to stop the machine, a treadle bar and connections from the treadle bar to each of the hereinbefore mentioned elements whereby the movement of the treadle bar actuates the said elements.

12. In combination with a sewing machine, variable speed driving mechanism and independent full speed driving mechanism therefor, stitching instrumentalities and means for causing them to skip a stitch, a tension

release, a stop motion, a treadle bar, connections from the treadle bar to each of the hereinbefore mentioned elements whereby the movement of the treadle bar actuates the said elements, a cam rotating with the driving mechanism, and means actuated by the cam to release the treadle bar at a predetermined point in the cycle of the machine.

13. In a machine of the character described, a variable speed clutch, a stop motion, a movable treadle bar which operates the variable speed clutch by one part of its movement and actuates the stop motion by another part of its movement, and a stop motion cut-out acting on the treadle bar to limit its range of movement to that part which actuates the variable speed clutch.

14. In a machine of the character described, a variable speed clutch, a stop motion, a movable treadle bar which operates the variable speed clutch by one part of its movement and actuates the stop motion by another part of its movement, said treadle bar having a notch of a length equal to the range of movement which operates the variable speed clutch, and a member movable into or out of the said notch to limit the range of movement of the treadle bar to that necessary to operate the clutch.

15. In a sewing machine, a barbed needle, a stitching shaft, connections from the shaft for oscillating the needle, means for changing said connections to give the needle a single abnormal stroke in the final stitch cycle, whereby it will not come to loop-receiving position and will carry no loop in final retracted position, and a timing device moving in time with the shaft for controlling said means.

16. In a sewing machine, a barbed needle, a stitching shaft, connections from the shaft for oscillating the needle, a stopping mechanism for stopping the machine with the needle retracted, and means for changing said connections to give the needle a shortened stroke in the final stitch cycle whereby it will not come to loop-receiving position, and will carry no loop in final retracted position.

17. In a sewing machine, a barbed needle, a stitching shaft, connections from the shaft for oscillating the needle, means acting when the machine is running forward for changing said connections to give the needle an abnormal stroke and a timing device moving with said shaft for operating said means.

18. In a sewing machine, a barbed needle, a stitching shaft, connections from the shaft for oscillating the needle, a stopping mechanism for stopping the machine with the needle retracted, and means for changing said connections upon stopping to give the needle an abnormally short advance followed by a similarly short retraction to restore normal conditions and leave the needle barb free of a loop.

19. In a sewing machine, a barbed needle, mechanism for giving the needle on each stitch cycle a normal advance and return stroke, means for applying a thread loop on the needle advance stroke, a stopping mechanism for stopping the machine with the needle retracted, and means for changing the needle advance stroke in the final stitch cycle to avoid taking the loop as the final 5 stitch cycle is performed, whereby the final needle retraction will be without loop.
20. In a sewing machine, a barbed needle, mechanism for giving the needle on each stitch cycle a normal advance and return stroke, means for applying a thread loop on the needle advance stroke, a stopping mechanism for stopping the machine with the needle retracted, and means for shortening the advance stroke of the needle to avoid taking 10 the loop, when performing the final stitch cycle whereby the final needle retraction is without loop.
21. In a chain stitch sewing machine, a stitching shaft, a needle, and actuating mechanism for reciprocating the needle uniformly cycle after cycle through a normal stroke, means operative during a cycle for rendering abnormal the needle stroke and a cam moving in time with the shaft for timing the action of said means.
22. In a sewing machine, a barbed needle, and actuating mechanism for reciprocating the needle uniformly cycle after cycle through a normal stroke, a stopping mechanism for stopping the machine with the needle retracted, and means operative during the final stitch cycle for shortening the needle stroke whereby to miss a loop upon stopping the machine.
23. In a sewing machine, a needle mechanism acting normally to reciprocate said needle through a given path of movement, connections acting while the machine is running forward for changing the stroke from the normal stroke to an abnormal stroke and a timing device moving with the needle actuating mechanism for controlling said connections.
24. In a sewing machine, a needle mechanism acting normally to reciprocate said needle through a given path of movement, stopping mechanism and connections acting while the machine is running forward for changing the stroke from the normal stroke to an abnormal stroke as the stopping mechanism acts to stop the machine.
25. In a sewing machine, a needle, a drive shaft, a driven shaft, means for detachably connecting said shafts, actuating mechanism connecting said needle with said driven shaft, connections acting while the machine is running forward for changing the stroke of the needle from the normal stroke to an abnormal stroke upon the disk connection 60 of the drive shaft from the driven shaft.
26. In a sewing machine, a barbed needle, a stitching shaft, connections from the shaft for oscillating the needle, means acting when the machine is running forward for changing said connections to give the needle an abnormal stroke, a stop device, a controller for applying said stop device, and devices associated with said controller and movable in timed relation to said shaft for determining the actuation of said connection changing means.
27. In a sewing machine, in combination, a stitching shaft, a barbed needle, connections for oscillating said needle from said shaft comprising a lever and a shiftable pivot therefor, a stopping mechanism for stopping the machine with the needle retracted, and means associated with said stopping mechanism for shifting said pivot whereby to give the needle a shortened stroke in the final stitch cycle.
28. In a sewing machine, a barbed needle, a stitching shaft, connections from said shaft for vibrating the needle comprising an oscillatory supporting member providing an eccentric pivot and a lever mounted to turn freely upon said pivot, means for stopping the machine with the needle retracted; controlling means for oscillating said supporting member whereby to give the needle a single abnormal stroke in the final stitch cycle, and a timing device moving in time with the shaft for determining the actuation of said controlling means.
29. In a sewing machine and in combination, a stitch-forming instrumentality having a normal path of movement during the formation of the stitch, a moving member actuating said stitch-forming instrumentality, an eccentrically mounted pivot on which said actuating member is pivoted, and means to rotate said eccentrically mounted pivot to cause the actuating member to vary the path of movement of the stitch-forming instrumentality.
30. In a sewing machine and in combination, a stitch-forming instrumentality having a normal path of movement during the formation of a stitch, an oscillatable member to actuate said stitch-forming instrumentality, an eccentrically mounted pivot on which said needle-actuating member is pivoted, and means to rotatably adjust said eccentrically mounted pivot so as to change the axis of oscillation of said actuating member and thereby vary the path of movement of the stitch-forming instrumentality.
31. In a sewing machine and in combination, a stitch-forming instrumentality having a normal path of movement during the formation of a stitch, an oscillatable member to actuate said stitch-forming instrumentality, means for actuating said oscillatable member, an eccentrically mounted pivot on which said needle actuating mem-

ber is pivoted, means to rotatably adjust said eccentrically mounted pivot at the will of the operator so as to change the position of the axis of oscillation of said oscillatable member and thereby vary the path of movement of the stitch-forming instrumentality.

32. In a sewing machine, in combination with a needle, an oscillatable actuating member to give reciprocating movement to the 10 needle, driving mechanism for actuating said needle moving member, an eccentrically mounted pivot on which said needle actuating member is pivoted, and means to rotatably adjust the eccentrically mounted 15 pivot on its axis at the will of the operator and thereby change the path of movement of the needle.

33. In a sewing machine in combination, with a needle, an oscillatable needle actuating 20 lever, a shaft, an eccentric on said shaft on which said lever is pivoted and which is normally in position for the lever to give a stitch-forming movement to the needle, means for oscillating the lever on said ec-

centric, a pinion on said shaft, a rack which 25 engages said pinion, and means controlled by the operator to actuate the rack and pinion to partially rotate the eccentric and thereby change the axis of oscillation of said needle actuating lever and change the path of movement of the needle.

34. In a sewing machine and in combination, a stitch-forming instrumentality having a normal path of movement during the formation of the stitch, an oscillatable member which actuates said stitch-forming instrumentality, a pivot on which said oscillatable member is mounted and means to change the position of the axis of said pivot and to thereby cause the actuating member 35 to vary the path of movement of the stitch-forming instrumentality, the axis of said pivot being stationary in its adjusted position during the oscillation of the actuating member.

In testimony whereof I affix my signature.

FELIX EMILE VALOIS.
